UNITED STATES PATENT OFFICE.

ANDREW J. SANFORD, OF NEWARK, OHIO.

DESIGN FOR A LIGHT-SHADE.

40,327.

Specification for Design.

Patented Nov. 2, 1909.

Application filed June 21, 1909. Serial No. 503,563. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

The drawing is a perspective view of a glass light shade showing my new design.

Its leading features comprise a series of

longitudinal prisms in the surface of a shade; each series of prisms being separated from the next series by a smooth face or facet substantially flat, or coinciding with the general surface of the shade.

I claim:

The ornamental design for a light shade, as shown and described.

ANDREW J. SANFORD.
